UNITED STATES PATENT OFFICE.

PAUL ETIENNE BARDONNAUT, OF TOULOUSE, FRANCE.

MEANS FOR PREVENTING NOISE OCCASIONED BY VIBRATIONS OF TELEGRAPH-WIRES.

SPECIFICATION forming part of Letters Patent No. 355,753, dated January 11, 1887.

Application filed July 17, 1885. Serial No. 171,874. (No model.) Patented in France January 6, 1885, No. 166,316.

To all whom it may concern:

Be it known that I, PAUL ETIENNE BARDONNAUT, a citizen of the French Republic, residing at Toulouse, in the French Republic, have invented certain new and useful Improvements 5 in Means for Preventing the Noise Occasioned by the Vibrations of Telegraph or Telephone Wires, (for which I have obtained Letters Patent in France, No. 166,316, dated January 6, 1885,) of which the following is a full, clear, and exact description, reference being had to the accompanying drawings, forming a part of this specification.

Referring to the drawings, Figures 1, 2, 3, 15 and 4 show in elevation various forms of sound-deadening springs interposed in the line-wire and connecting said wire with its rigid support.

It is well known that aerial conductors of 20 electricity are subjected to vibrations that result in more or less noise, according to the degree of vibration, which latter is due to atmospheric influences.

I have found that when a resilient medium— 25 such as a coiled spring—is interposed in the electric conductor itself in close proximity to the insulators, or if said insulators are supported from a resilient medium, or if the conductor itself is supported from such a medium, 30 the noise inherent to or produced by the vibrations of the conductor is effectually avoided.

The invention consists, essentially, in the interposition of a spring in the conductor or line-wire itself of which such spring then forms 35 a part and serves as a connection between the line-wire and its insulators or rigid supports.

In carrying out my invention I interpose in the line-wire a connection, A, provided with the volute portions *a a*, which perform the 40 functions of springs, as shown in Figs. 1 and 2. This connection is secured to the insulator B, its ends being secured to the ends of the line-wire *w* by any suitable means—as, for instance, by means of muffs or sleeves *m m*.

In Figs. 3 and 4 the spring portions *a a* of 45 the connection differ in shape from those shown in the preceding figures. In Fig. 3 the springs are shown as having a spiral form, while in Fig. 4 the diameter of the spirals of the spring increases from the ends of the springs toward 50 the center, forming double conical springs.

The sleeves or muffs *m m*, or connections between the ends of the wire and the ends of the connection A, are of the ordinary kind. By the use of the arrangement of devices shown 55 in Fig. 1 an additional advantage is obtained in that the wires are allowed a certain amount of contraction without any liability of breakage.

I do not desire to claim, broadly, the interposition of a spring breaking the continuity of an electric conductor and forming a resilient joint, as this has been done in underground lines for compensating the contraction and expansion in such conductors; but I believe I 65 am the first to use a resilient spring for counteracting the noise due to the vibrations of aerial conductors.

Having now described my invention, what I claim is—

The combination, with an aerial conductor of electricity or a line-wire and its rigid support, of a resilient conductor interposed in and forming a continuation of said line-wire and connecting the same with its rigid support for the purpose of deadening the sound due to the vibrations of the line-wire, as described.

In testimony that I claim the foregoing I have hereunto set my hand this 26th day of May, 1885.

PAUL ETIENNE BARDONNAUT.
